UNITED STATES PATENT OFFICE.

WILLIAM C. GHOLSON, OF CINCINNATI, OHIO.

FENCE-POST.

SPECIFICATION forming part of Letters Patent No. 425,317, dated April 8, 1890.

Application filed September 7, 1889. Serial No. 323,287. (No model.)

To all whom it may concern:

Be it known that I, WILLIAM C. GHOLSON, a citizen of the United States, residing at Cincinnati, in the county of Hamilton and State 5 of Ohio, have invented certain new and useful Improvements in Fence-Posts; and I do hereby declare the following to be a full, clear, and exact description of the invention, such as will enable others skilled in the art 10 to which it appertains to make and use the same.

My invention relates to fence-posts; and it consists of the structure hereinafter described and illustrated.

15 My invention is a simply constructed and inexpensive metal post, and is especially adapted for use with wire or barbed wire, and its principal object is to save the expense of wooden posts, particularly in those regions 20 where suitable wood or timber is scarce.

It is illustrated in the accompanying drawings, in which—

Figure 1 is an end view in elevation of one 25 side of the complete post ready for use; Fig. 2, a similar side view; and Figs. 3, 4, and 5, details of fastening devices.

30 A A' are two bars of V-shaped angle-iron, with the ends of the diverging arms brought face to face, but a slight distance apart to admit of fastening devices being inserted between the bars to hold them together. These 35 bars, preferably made of steel, are rolled and cut in lengths, and then bent outwardly at their ends, as shown, for the purpose of securing a foot-piece B between them to anchor the post more securely in the ground. The 40 foot-piece B is wedge-shaped and is preferably made of wood. The base and bars are held together by means of a strong wire C. The inner edges of the arms of the bars fit 45 snugly against the sides of the foot-piece, and when the latter is made of wood the drawing and twisting of the wire around both bars and foot-piece will draw and hold them exceedingly tight together.

In Fig. 3 is shown one form of soft sheet-steel or other suitable metal fastening D. It is slotted at each end, making four wings. The bracket is then put between the bars 50 and its ends bent in opposite directions and hammered solidly against the sides of the

bars; or substantially the same bracket can be made by doubling two pieces of metal, riveting them together at the center, then passing the bracket between the bar, and turning the ends down, as before. 55

Another form of bracket E is shown in Fig. 4, in which two pieces of metal or washers are bent to conform to the contour of the bars, and are held together and to the bars by a screw-bolt, and tightened by a nut. The space formed between the bars by the brackets placed between them forms an open eye or slot through which brackets, staples, or bolts can be passed for the fastening or attachment of the fence-wire. 65

In Fig. 5 I have shown a modification of the post in the shape of the bars at the bottom. Instead of the bars being bent at an angle to accommodate a wedge-shaped bottom piece, as before described, they may be bent at a curve and made fork-shaped, with the ends straight, as shown, so as to embrace a round or square base. In either case the 70 bars and fastenings can be made and sent to 75 the user, who can adapt them to any form of base-piece desired.

What I claim is—

1. A fence composed of two bars of angle-iron with their divergent arms brought face 80 to face, and having their lower ends bent outward, in combination with an underground foot-piece placed between and embraced by said lower expanded ends, brackets to hold said bars together, and a metal fastening 85 stretched around the bars and foot-piece to draw and hold the same together, substantially as described.

2. The combination, with the two angle-bars A A' of the bracket E, formed of two 90 pieces of metal bent to conform to the contour of the bars, and the screw-bolt and nut by which said parts of the bracket are held together and against the said bars, as shown and described. 95

In testimony whereof I affix my signature in presence of two witnesses.

WILLIAM C. GHOLSON.
